UNITED STATES PATENT OFFICE.

EARL E. DANA, OF STOCKPORT, IOWA.

CHAIN-CLASP.

1,377,187.

Specification of Letters Patent. Patented May 10, 1921.

Application filed January 27, 1921. Serial No. 440,392.

To all whom it may concern:

Be it known that I, EARL E. DANA, a citizen of the United States, residing at Stockport, in the county of Van Buren and State 5 of Iowa, have invented a new and useful Chain-Clasp, of which the following is a specification.

This invention relates to clasps, and more particularly to clasps employed for connecting the ends of chains, it being the primary 10 object of the invention to provide a clasp which will be locked to the chain to eliminate accidental displacement thereof.

A further object of the invention is to 15 provide a clasp of this character of a novel construction adapting the same for use especially with anti-skid chains for motor vehicle tires.

A still further object of the invention is 20 to provide means forming a part of the clasp for retaining the free end of the chain out of contact with the locking means when the chain is to be removed.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

35 Referring to the drawing:—

Figure 1 illustrates a sectional view through a clasp constructed in accordance with the present invention, the locking member being shown in an unlocked position.

40 Fig. 2 illustrates a plan view of the clasp showing the locking element in its locked position.

Referring to the drawing in detail, the 45 clasp includes a body portion 5 which may be formed in any suitable design, to meet various requirements for which the device is to be used.

The body portion 5 is provided with a cut 50 out portion 6 forming a hook member 7, which hook member is designed to be positioned behind one link of the free end of the chain, or flexible element, which has connection with the clasp, and which is to be locked thereto, in a manner to be hereinafter more fully described.

Formed in the body portion 5, and extending from one edge thereof, is a cut out portion 8, the lower wall of which is provided with a lug 9, which has one edge thereof curved to 60 conform to the curvature of the link 10, which as shown, engages therewith, the lug 9 being for the purpose of supporting the link and holding the same while the locking member is being positioned. After 65 the locking member has been positioned, the link 10 is moved to contact with the curved wall 11, of the cut out portion 8 where the same is retained.

This locking member is indicated by the 70 reference character 12, and is formed preferably of sheet metal, bent intermediate the side edges to provide opposed flanges 13 adapted to contact with the side faces of the body 5, and as shown, the locking member 75 12 has pivotal connection with the body portion 5 as by means of the bolt 14, which passes through the flanges 13, and a suitable opening formed in the body portion 5.

Formed in the respective flanges 13 and 80 disposed at points opposite each other, are the cut out portions 15, one wall of which is provided with an extension 16, which, when the locking member 13 is in its locking position will restrict the opening formed by 85 the cut out portions 15 to eliminate any possibility of the link 10 passing from the opening in which the same is positioned.

The bolt 14 is relatively long and has its 90 ends extending beyond the side walls of the locking member 13, where the same receives the twisted ends 17 of the link member 18, which permanently connects one end of the chain to the clasp.

In order that the locking means 13 may 95 be easily and readily operated, a notch 19 is formed therein to accommodate the thumb nail of the operator, whereupon the locking member 12 may be pivoted to its open position if it is desired to disconnect the free 100 end of the chain therefrom.

In the operation of the device, the link 10 is positioned behind the hook member 7, while the chain is being stretched around a tire, and when the chain has been properly positioned, the link 10 is moved to a position over the lug 9 to the end that the link is held in a position out of the path of travel of the locking member 12, when the same is moved to a locking position.

110 It is obvious that when the locking member is moved to a position as indicated in

dotted lines as in Fig. 1 of the drawing, the link member 10 may be moved to contact with the curved wall 11, with the result that the link may only be removed by 5 moving the locking member 12 to its unlocked position.

Having thus described the invention, what is claimed as new is:—

In a clasp, a body portion having a cut 10 out portion extending from one of the side edges thereof, a lug formed on one of the walls of the cut out portion, a hook member formed adjacent to one end of the body portion, said lug adapted to engage a link of 15 a chain, a pivoted locking member embrac-

lug the body portion and extending inwardly terminating at a point flush with one edge of the lug to permit the locking member to move thereover, and said locking member having an opening adapted to register with the cut out portion of the locking member. 20

In testimony that I claim the foregoing as my own, I have hereto affixed my signature in the presence of two witnesses.

EARL E. DANA.
